F. C. BARTON.
TEMPERATURE COMPENSATOR FOR ELECTRICAL CONTROL DEVICES.
APPLICATION FILED DEC. 20, 1916.

1,313,051.

Patented Aug. 12, 1919.

Inventor:
Frederick C. Barton,
by *Alfred C. Cain*
His Attorney.

UNITED STATES PATENT OFFICE.

FREDERICK C. BARTON, OF FORT WAYNE, INDIANA, ASSIGNOR TO GENERAL ELECTRIC COMPANY, A CORPORATION OF NEW YORK.

TEMPERATURE-COMPENSATOR FOR ELECTRICAL CONTROL DEVICES.

1,313,051.

Specification of Letters Patent.

Patented Aug. 12, 1919.

Application filed December 20, 1916. Serial No. 137,966.

To all whom it may concern:

Be it known that I, FREDERICK C. BARTON, a subject of the King of Great Britain, residing at Fort Wayne, county of Allen, 5 State of Indiana, have invented certain new and useful Improvements in Temperature-Compensators for Electrical Control Devices, of which the following is a specification.

10 My invention relates to temperature compensators for electrical control devices and particularly to temperature compensators for vibratory regulators.

An object of my invention is to provide 15 improved temperature compensating means whereby the operation of the electrical control device, to which said means is applied, whether it be an automatic regulator, a combined regulator and reverse current 20 cut-out, or other device, will be uniform at all times and practically independent of the temperature of the device.

Another object of my invention is to provide a voltage regulator, comprising an 25 electromagnet having a voltage winding, a vibratory contact operated by said winding, and a non-vibratory contact coöperating with said vibratory contact, with thermostatic means associated with the non-vibratory 30 contact to adjust the position thereof in response to temperature changes in the regulator to compensate for the effect of said changes upon the responsiveness of said voltage winding.

35 For a better understanding of my invention, reference may be had to the accompanying drawings, in which the single figure illustrates, for the most part diagrammatically, one form of my invention embodied in a system of regulation for a direct current generator. In said figure I have illustrated my invention applied to a combined regulator and cut-out shown in connection with a system which comprises a 40 direct current generator 1, having a shunt field winding 2 and an adjustable shunt field resistance 3. This generator, which may be driven by any suitable means, is arranged to supply current for charging the

storage battery 21 and for lights or other 50 translating devices 22.

Interposed between the generator and the translating devices is a combined regulator and cut-out mechanism having coöperating contacts 4 and 5 which are adapted 55 through suitable connections to short circuit the field resistance 3. The contact 4 is adjustably mounted in a member 9 which is supported by means of the thermal member 7-8 upon the member 6, which is 60 attached to the casing of the regulator.

The members 7 and 8 have unequal coefficients of expansion so that changes in the temperature to which they are subjected will effect a raising or lowering of the 65 member 9 and the contact 4 carried thereby.

The contact 5 is carried by the armature 13 which is supported by means of a spring 10 formed of a light, thin, flat ribbon of spring steel, rigidly attached at its ends 70 to fixed supports 11 and provided intermediate the moving contact and the ends with relatively large loops 12. The armature 13 is adapted to coöperate with the core 14 of an electromagnet. 75

I have illustrated this electromagnet as provided with a plurality of windings, one of which, designated by the number 15, is connected across the armature of the generator and the other of which, designated 80 by the number 16, is interposed between the generator and the storage battery. The translating devices 22 are connected, as shown, to an intermediate tap on the winding 16. 85

Coöperating with one end of the core 14 is an armature 17 mounted upon a pivoted member 18 which carries a contact 19 adapted, when the armature 17 is in its attracted position, to engage with the fixed 90 contact 20 to connect the generator to the winding 16.

I at present understand the operation of the combined regulator and cut-out with my improvement embodied therein to be as 95 follows: Assume that the generator 1 is driven by any means having variable speed. When the voltage of the generator is below

a predetermined value, the contacts 4 and 5 will be in engagement and consequently the resistance 3 will be short circuited thereby. This condition enables the generator to build up rapidly, and when a predetermined voltage is reached, the voltage winding 15 will be energized to an extent sufficient to attract the armature 17 carried by the member 18, and hence to connect the 10 battery 21 and the translating devices 22 through the series winding 16, contact 20, and contact 19, to the generator. The arrangement of windings 15 and 16 is such that current flowing from the generator to 15 the battery and translating devices will cause the winding 16 to assist the voltage winding 15.

Upon the voltage increasing to a certain higher value, the armature 13 will be attracted due to the effect of the windings 15 and 16 and consequently the contacts 4 and 5 will be disengaged and the resistance 3 inserted in the field of the generator. The design of the generator field winding 2 and 25 resistance 3 is such that, if the resistance 3 continue short circuited the generator will maintain a voltage higher than that desired, whereas if the resistance continue in series with the field winding 2 the generator will 30 maintain a voltage below that desired. These maximum and minimum values of the generator voltage are such that the armature 13 and hence the contact 5 are caused to vibrate as the generator voltage fluctuates from the maximum to the minimum value. This vibration produces a regulation 35 of the generator voltage in a well known manner. The winding 16, since it is cumulative with respect to winding 15, modifies, 40 according to the amount of current flowing from the generator to the battery and translating devices, the operation of the regulator.

The winding 16 furthermore acts, in case 45 the voltage of the generator falls below that of the battery and current consequently tends to flow to the battery from the generator, differentially with respect to the winding 15 and permits the contact 19 to be 50 moved by gravity, or otherwise, out of engagement with contact 20.

In the operation of the regulator it is obvious that in case the temperature of the windings varies, the resistance thereof will 55 vary, and that in case the resistance of the voltage winding 15 fluctuates, the current flowing therein in response to a given voltage impressed thereon will likewise fluctuate, and hence the attractive power of said 60 winding upon the armature 13 for any given voltage across its terminals will vary. This non-uniformity of the action of winding 15 at different temperatures is an objectionable feature. The effect of the variation in

temperature is, according to my invention, 65 nullified by mounting the non-vibratory contact in the support 9, the position of which is varied by means of the thermostatic members 7 and 8, so that upon a rise in the temperature of the regulator the non-vibratory contact 4 will tend to move away from the vibratory contact 5 and with a reduction in the temperature said non-vibratory contact 4 will tend to move toward the vibratory contact 5. This thermostatic adjustment of the non-vibratory contact results 70 in the modification of the relative periods during which contacts 4 and 5 are engaged and disengaged, and hence of the relative periods during which the resistance 3 is respectively short circuited and in series with the field winding 2.

While I have shown and described one form of my invention applied to one type of electrical control device, it is, of course, 85 obvious that my invention is not limited to the specific structure shown nor to the particular application illustrated, and I seek to cover in the appended claims all modifications and variations that come within the 90 spirit and scope of my invention.

What I claim as new and desire to secure by Letters Patent of the United States is,—

1. In an electrical control device, the combination of a non-vibratory contact, a vibratory contact adapted to coöperate therewith, electro-responsive means adapted to actuate said vibratory contact, and thermostatic means for adjusting the position of said non-vibratory contact in response to temperature changes.

2. In an automatic regulator, the combination of an adjustable non-vibratory contact, a vibratory contact adapted to coöperate therewith, electro-responsive means comprising a winding adapted to actuate said vibratory contact, and supporting means for said non-vibratory contact comprising a plurality of members having different coefficients of expansion and adapted 105 to vary the position of said non-vibratory contact in response to temperature variations of the regulator.

3. In an automatic regulator, the combination of an adjustable non-vibratory contact, a vibratory contact adapted to coöperate therewith, electro-responsive means comprising a voltage winding adapted to actuate said vibratory contact, and supporting means for said non-vibratory contact comprising a pair of parallel members having different coefficients of expansion and adapted to vary the position of said non-vibratory contacts in response to temperature variations of the regulator.

4. In an automatic regulator, the combination of an adjustable non-vibratory contact, a vibratory contact adapted to coöp-

erate therewith, a looped spring rigidly supported at its ends for supporting said vibratory contact, electro-responsive means comprising a voltage winding adapted to 5 actuate said vibratory contact and supporting means for said non-vibratory contact comprising a pair of parallel members

having different coefficients of expansion and adapted to vary the position of said non-vibratory contact in response to temperature variations of the regulator. 10

In witness whereof, I have hereunto set my hand this 15th day of December, 1916.

FREDERICK C. BARTON.
